UNITED STATES PATENT OFFICE.

ROBERT J. EVERITT, OF NEW YORK, N. Y., ASSIGNOR OF ONE-HALF TO
RICHARD GASAU, OF SAME PLACE.

SPRING BED-BOTTOM.

SPECIFICATION forming part of Letters Patent No. 624,634, dated May 9, 1899.

Application filed February 25, 1898. Serial No. 671,631. (No model.)

To all whom it may concern:

Be it known that I, ROBERT J. EVERITT, a citizen of the United States, and a resident of New York, in the county of Kings and State of New York, have invented a new and useful Improvement in Spring Bed-Bottoms, of which the following is a specification.

This invention relates to certain improvements in spring bed-bottoms, the object being to provide a bed-bottom which may be easily detached for the purpose of cleaning, stowage, or removal, which may be easily replaced in its position, and in which springs may be tightened or loosened by a single operation for adjusting the bed-bottom, as may be required.

A further object is to provide means for suspending the bed-bottom from the posts of the bedstead rather than from its end rails, as has heretofore been usual.

A practical embodiment of my invention is represented in the accompanying drawings, in which—

Figure 1 represents a top plan view of the bed-bottom and bedstead, portions of the same being broken away to more clearly show the means for suspending the bed-bottom. Fig. 2 represents a side view of the same, and Fig. 3 represents a vertical longitudinal section taken in the plane of the line 3 3 of Fig. 1.

The portions of the bedstead herein represented consist of head-posts A A' and foot-posts A² A³, connected by side and end rails a a' a² a³ in the usual manner. The bed-bottom proper comprises head and foot cross-rails B B', connected by the springs B², which springs are herein represented as of the woven-wire type.

Split brackets C C' are clamped securely to the foot-posts A² A³ at points a short distance above the rails of the bedstead. Each of these brackets comprises two members c c', secured together by bolts c², one of which members—in the present instance the member c'—is provided with a headed stud or pin c³. The cross-rail B' of the bed-bottom is provided with two eye-plates b, having elongated eyes b' therein, which eyes have enlarged and reduced portions, the enlarged portions permitting the insertion of the studs

c³ and the reduced portions serving to engage the heads of the said studs for removably locking the cross-rail B' to the brackets C C'.

Split brackets D D' are clamped rigidly around the head-posts A A' at points just above the bedstead-rails, each of the brackets comprising two members d d', secured together by bolts d². These brackets D D' are provided with downwardly and inwardly extended recesses d³, opening through the front edges of the said brackets.

A rotary shaft E is adapted to be removably supported at its ends in bearings in the said recesses d³, one or both of the ends of the said shaft exterior to the recesses being provided with a squared portion e for the engagement therewith of a wrench for use in turning the said shaft. The means which I have shown for connecting the said shaft with the head cross-rail of the bottom, so as to tighten or loosen the springs by the turning of the shaft, comprise a pair of wheels having flexible connections secured thereto and to the head-rail, which flexible connections are arranged to be wound and unwound on the peripheries of the said wheels. In the present instance I have represented these wheels as having sprockets F F' mounted in close proximity to the inner faces of the brackets D D'. The flexible connections are represented as sprocket-chains f f', adapted to engage the teeth upon the said sprocket-wheels, the inner ends of the said chains being provided with hooks f² f³, which are removably engaged with eye-plates b², carried by the head cross-bar B.

To prevent the sprocket-wheels from unwinding unintentionally, and thereby loosen the bed-bottom, I provide the shaft E with ratchet-wheels G G', which ratchet-wheels are located between the sprocket-wheels and the inner faces of the head-brackets D D'. Gravity-pawls g g' are mounted on the inner faces of the said head-brackets with their noses in position to engage the teeth upon the ratchet-wheels G G'. These pawls may be provided with thumb-pieces g² g³, if found desirable, for use in releasing the pawls when it is desired to permit the sprocket-wheels to unwind—as, for instance, when it is desired to remove the bed-bottom. To partially support the bed-

bottom at its head portion, the head cross-rail may be provided with legs H H', which rest upon the side rails *a a'* of the bedstead. These legs do not in any way interfere with the tightening and loosening of the bed-bottom, as they will travel along the tops of the said rails during this operation. In the present instance these legs are separate pieces secured permanently to the said head cross-rail at points over the side rails. By this windlass arrangement for tightening and loosening the bed-bottom the tension of the springs may be adjusted to a nicety by a single movement, thus doing away with the necessity of adjusting a number of bolts to produce the desired result. When it is desired to remove the bed-bottom from the bed, the pawls are lifted away from engagement with their ratchets and the shaft E is then permitted to rotate, and thus loosen the flexible connections *ff'*. The head-rail may then be disengaged from the said flexible connections and the foot-rail may be released from its engagement with the brackets at the foot of the bed. The bed-bottom may then be rolled up into a compact bundle.

If it is desired to remove the adjusting mechanism from the bed, the shaft E and its sprocket and ratchet wheels may be lifted out of the recesses *d³* in the head-post brackets.

It is evident that the devices for removing

and adjusting the bed-bottom may be reversed, and it is also evident that slight changes might be resorted to in the form and arrangement of the several parts without departing from the spirit and scope of my invention. Hence I do not wish to limit myself strictly to the structure herein set forth; but

What I claim is—

The combination with a bedstead, of a pair of brackets secured to the posts at one of its ends, a bed-bottom having one of its ends engaged with the said brackets, a pair of brackets secured to the posts at the other end of the bedstead and an adjusting mechanism comprising a rotary shaft and flexible connections between the said shaft and the adjacent end of the bed-bottom, the said last-named pair of brackets having downwardly and inwardly extended recesses opening through their outer edges for the reception of the said rotary shaft whereby the shaft is located on the outer side of the posts, substantially as set forth.

In testimony that I claim the foregoing as my invention I have signed my name, in presence of two witnesses, this 21st day of February, 1898.

ROBERT J. EVERITT.
